UNITED STATES PATENT OFFICE.

WILLIAM KARL AND HEINRICH KARL, OF JERSEY CITY, NEW JERSEY.

TOOTHBUSH.

Application filed November 10, 1917. Serial No. 201,364.

To all whom it may concern:

Be it known that we, WILLIAM KARL, a citizen of the United States, and HEINRICH KARL, a citizen of Germany, residing at 5 Jersey City, county of Hudson, State of New Jersey, have invented certain new and useful Improvements in Toothbrushes, of which the following is a specification.

The present invention relates to improvements in tooth-brushes, and has for its object to provide means by which the bristles of a tooth-brush may be protected against breakage at their points of connection to the handle or backing. At the same time 10 this invention provides means by which the bristles would be impregnated, and thereby rendered more elastic and therefore more resistant to wear.

A further object is to provide a brush 20 which will be moisture-resisting, so that the bristles will not absorb water. In this way the life of the brush will be materially increased.

With our improvements we further provide a brush which will have improved 25 cleansing properties that is, it will polish and clean the teeth in a manner not possible with the ordinary tooth-brush.

With this and other objects in view embodiments of our invention are shown in 30 the accompanying drawings, and these embodiments will be hereinafter more fully described with reference thereto, and the invention will be finally pointed out in the 35 claims:

In the accompanying drawings:

Fig. 1 is a side-elevation of a tooth-brush embodying our invention;

Fig. 2 is a horizontal sectional view taken 40 along the line of 2-2 of Fig. 1;

Fig. 3 is a vertical sectional view taken along the line of 3-3 of Fig. 1;

Fig. 4 is a perspective view showing a device employed in manufacturing the brush 45 of our invention;

Fig. 5 is a plan view of this device.

Fig. 6 is a perspective view of a tool for use in applying a compound used in constructing a tooth-brush embodying the invention, a portion of the brush being shown 50 in dotted lines; and

Fig. 7 is a side elevation of a brush embodying a slightly different form of the invention.

55 Similar reference characters indicate cor-

responding parts throughout several figures in the drawings.

Referring to the drawings, the brush comprises a handle and hard backing, in which the bristles 20 are inserted in the usual manner. A cord or string 21 is entwined about the bristles adjacent the backing, and a soft compound 22 which may also be elastic and flexible is formed about the lower portion of the bristles. The cord 21 is imbedded in the compound 22, the purpose of the cord being to reinforce the compound if it is an elastic one, and at the same time to hold the compound securely with relation to the bristles. 60

The compound 22 must have certain characteristics: for instance it must not be injurious to the teeth or gums. It cannot, therefore, be a very hard substance but must on the contrary be quite soft. The degree of softness of the compound is preferably such 70 as to cause it to wear slightly when the brush is in use. As one embodiment we propose to employ para rubber, which is of a very soft, and at the same time elastic and flexible, character. Of course other materials 75 which do not contain ingredients injurious to the teeth may also be employed.

We propose to mix rubber with particles of cord or cork-dust or other material which will not be injurious to the teeth. In some 85 cases it may be preferable to apply two or more layers 35, 36, and 37, all of different substance, and in such cases we may provide as the top layer 37 para rubber which has a property of constituting polishing 90 means for the teeth.

While we have shown an elastic and flexible compound, as extending a short way along the bristles, it will be understood that it may be only a thin layer extending slightly 95 above the base or it may, if desired, reach almost to the end of the bristles leaving only the points free.

The bristles may be impregnated with oil or other moisture-resisting substances prior 100 to the application of the compound to them, especially if the compound which is to be applied, consists of rubber, but we may provide a compound or compounds which are themselves mixed with a suitable oil. In the case last mentioned, the oil or the compound 105 may be caused to impregnate the bristles in a very thorough manner thus rendering a special impregnation of the bristles unnecessary. A special impregnation of the bristles 110

is recommended only in the case of employment of a single compound 22 consisting of rubber or other suitable material. Under such conditions it is desirable that the 5 bristles be separately impregnated before the compound is applied to them, because oil cannot be added to or mixed with rubber in such a way as to cause an efficient impregnation of the bristles. When the bristles of 10 a brush are thus impregnated the brush will be moisture-resisting and the bristles will not become water-soaked.

We know that it has heretofore been proposed by others to use certain materials such 15 as cement and rubber, the latter being usually vulcanized, for holding the bristles of a brush firmly in the backing. Inasmuch, however, as the substance thus used were intended to serve only to secure the bristles 20 to the backing, they were so arranged as in reality to form merely a molded portion of the backing, and even when the compounds composed of rubber were made hard, as by vulcanization, they became injurious to the 25 teeth or gums if brought in contact with them when using the brush. The compounds employed by us act on the other hand not only to prevent breakage of the bristles, but also to provide a polishing medium for the 30 teeth, and other purposes for which the construction of the prior art are not adapted.

Accordingly the compound or compounds used by us are located on different parts of the bristles from the molded-backing-members proposed by others, and possess characteristics different from those of such backing members.

In carrying out our invention it will be understood that any suitable material having 40 the properties desired may be employed, but preferably these should be such that they will not have a bad taste, as well as not be injurious to the teeth.

With our improvements it will be seen that 45 the bristles are supported by means additional to those usually employed on tooth-brushes, and therefore applied to parts of the bristles which on other tooth-brushes are left free. The grip upon the bristles and the 50 protection afforded them is therefore such that danger of the bristles breaking off or pulling out is entirely obviated. In the old forms of brushes, the bristles would very soon break off after very little use, the breaking 55 occurring usually at their base, this being the result of the bristles becoming too brittle.

In our invention the bristles may be sufficiently stiff to properly cleanse the 60 teeth, and at the same time they are so flexibly supported that they will not break off.

It should also be mentioned that the oiling alone will not suffice to render the bristles continuously elastic and therefore resistant 65 to breakage, because the oil will be gradually

removed from them during the use of the brush, it being understood that the subjection of the brush to hot or warm water, and the use of the brush with divers tooth-cleaning powders, or pastes, will tend to 70 remove the oil. Therefore more substantial protection of the bristles than would be afforded by oil alone is required, and this we provide with the compounds set forth.

The compound 22 may be applied in various ways, the one herein employed consisting in the use of a tool shown in Figs. 4 and 5, and another tool constructed as shown in Fig. 6.

In order to apply the compound 22 in a 80 neat manner, a tool such as shown in Figs. 4 and 5 may be employed. This tool shown in Figs. 4 and 5 consists of a sheet of metal 10 having a slit 11 adapted to embrace the bristles, the side portions of the sheet being 85 bent upwardly and inclined oppositely from each other. The bristles of the brush are placed in the slit and held together, whereby the compound 22 will be confined to its proper shape. The tool shown in Fig. 6 90 comprises a sheet 30 of metal sharply bent midway its side edges, as shown at 30^a and having a slit 30^b which extends a portion of its length.

This tool is used for applying the compound 22 between the rows of bristles, and between the individual bristles as illustrated in Fig. 6 whereby the bristles are divided by the portions of the sheet 30 and the compound 22 will be poured or placed in the 100 space between the two upwardly bent inclined portions 30^a and 30^b of the device. A slight pressure will force the compound through the slit 30 and cause it to contact with the base portion of the bristles and with the backing. This method of applying the compound prevents smearing of the tips of bristles with the compound, and by turning the tool horizontally, soiling of the outer 105 portions of the bristles by the compound, 110 will be avoided.

We have illustrated and described a preferred and satisfactory embodiment of our invention, but it is obvious that changes may be made therein within the spirit and scope thereof as defined in the appended claims, and that the invention may be embodied in other brushes than tooth-brushes, as for instance cloth-brushes, hair-brushes, etc.

What we claim as new and desire to secure by Letters Patent is—

1. In a tooth-brush, a base, bristles set in said base, an elastic, adhesive compound disposed upon said base and imbedding the bristles over a portion of their length between their base portions and their tip ends, said compound serving to support the bristles yieldingly adjacent to their base portions to prevent sharp bending and breakage.

2. In a tooth-brush, a base, bristles set in said base, a latterly disposed cord entwined about said bristles adjacent said base, and an elastic compound disposed upon said base, and imbedding said bristles adjacent their ends set in said base and gripping said cord, and constituting a flexible strengthening means adapted to prevent breaking off of the bristles set in said base.
- 10 3. In a tooth-brush, a base, bristles set in said base, and an elastic compound having a finely divided polishing substance mixed therein, said elastic compound disposed upon said base and imbedding the bristles adjacent their ends set in said base, constituting a flexible strengthening means adapted to prevent breaking off of said bristles adjacent said base.
- 15 4. In a tooth-brush, a base, bristles set in said base, an elastic adhesive compound disposed upon said base, embedding the bristles
- for a portion of their length between their base portion and their tip ends, said compound serving to support the bristles yielding adjacent their base portion to prevent 25 breaking of the bristles, the bristles being also impregnated with oil to make them resistant to the absorption of water, and to render them less brittle.
5. In a tooth-brush, a backing, a compound disposed upon said backing embedding the bristles between the base and the points thereof for holding the bristles straight and rendering them resistant to breakage, and another compound disposed upon said first- 30 mentioned compound and being mixed with cork particles constituting a harmless cleansing and polishing means for the teeth in co-operation with the bristles.
